UNITED STATES PATENT OFFICE.

WILLIAM A. DARAH, OF CHICAGO, ILLINOIS.

TELEPHONE HORN.

Application filed May 12, 1924. Serial No. 712,808.

To all whom it may concern:

Be it known that I, WILLIAM A. DARAH, a citizen of the United States, residing at Chicago, in the county of Cook and State 5 of Illinois, have invented a new and useful Improvement in Telephone Horns, of which the following is the specification.

This invention relates to acoustic devices such as telephone "loud speakers", announcing equipment, phonographs and other sound producing or reproducing equipment.

The object of this invention is to provide a strong, durable, equipment, which permits the emission of sound waves of maximum loudness without distortion. Another object of this invention is to provide a horn which will give approximately the same amplitude of sound wave for the same energy input over substantially the entire 20 range of audible frequencies.

Other objects of this invention will appear from the appended drawings and the specification.

These objects I attain by means of the 25 construction and the material employed, as herein described and illustrated.

In the drawings Figure I shows a front elevation of my invention looking into the horn. Figure II shows a vertical section 30 through one form of my invention, the section being taken on the line BB of Figure III. Figure III shows a plan view looking down on my device from the top, while Figure IV shows a vertical section 35 through the device taken along the line AA of Figure III. Figure V shows a detail of the sound passage at a point near the source.

Referring to the drawing, (1) indicates 40 the device, which may be made of porcelain, stoneware, earthenware, and other hard, dense ceramic materials. The material must be strong, hard, rigid and preferably have a surface which is smooth and glazed.

The device consists of a horn (2) which 45 is formed of the ceramic material referred to above, and provided with an opening (3) which tapers to a constriction (4) and which then continues to reduce in section 50 until at the point (5) it is connected to a source of sound waves (6), which may be a telephone receiver, a phonograph receiver, musical device or other sound producing or reproducing equipment. For purposes 55 of simplicity this is described as a telephone receiver, and the device in this case will be

used for the so-called loud speaker or amplifying unit which is commonly employed in wireless telephones, public speaking systems, train announcing, etc.

The washer (7), which may be formed from lead, fibre, rubber, felt, or some deformable material, is placed between the end of the horn (5) and the mouthpiece of the telephone receiver (6). The base of the telephone receiver (8) is held in close contact with the constriction of the horn (5) by means of a resilient member (9) which is fastened by screw (10) to the housing (11) of the horn. A nut (12) on the screw (10) serves to firmly attach the resilient member (9) to housing (11).

(13) represents the wires or leads to the telephone receiver. (14) indicates the side walls of the horn, which also serve to enclose the sound producing instrument. These walls aid in making the horn rigid and free from vibrations. (15) represents the tubular constriction connecting throat (4) with orifice (5). (16) represents the telephone diaphragm.

The housing 11 is created by a curved rib at the rear of the horn, which at its ends, merges into the longitudinal ribs 11* that extend under and are formed integrally with the body of the horn. These ribs 11 and 11* not only combine to support the horn in its operative position but add to its inherent and natural rigidity.

I have found that the constriction of the horn should preferably be such that the section area at any one place changes by an approximately constant exponential factor. This may be illustrated by the formula $A_1 : A_2 = K^c$, where "c" is a constant exponential function. This arrangement appears to give the minimum losses by reflection and therefore the maximum efficiency. This arrangement also causes the device to widely depart from a condition of resonance or tuning. Resonance is of course objectionable in that the device if tuned or resonant will respond more markedly to the frequencies of resonance than to the other audible frequencies. For example, a straight tube would be very objectionable owing to its resonating tendency with a small group of wave lengths.

I have found that very appreciable losses in horns, as well as the presence of overtones and harmonics, result from the use of materials which can vibrate or yield to the

varying pressure of the sound waves. For example, thin sheet metal, by reason of the vibration set up within the horn material, results in distorting the sound produced and is of such form and contour that it may be conveniently placed on any table or support without occupying a great deal of space.

5 absorbing an appreciable portion of the sound energy. On the other hand, a horn whose walls are made of rigid, solid, glazed porcelain, glass or ceramic materials, is not subject to vibration or motion under the influence of sound waves, and therefore absorbs none of the energy of these waves and does not introduce resultant reflections or distortion or over-tones.

10 So important is this factor, that certain inferior horns which are now being made from papier mâché and other relatively soft materials, are given a treatment with hard varnish or shellac, or related substances, to harden the walls and thereby somewhat improve them, although these are still very imperfect.

15 As a graphic illustration of this principle, the analogy would be somewhat similar to that of a railroad train running upon rubber rails instead of steel rails. In this case, owing to the compression of the rubber by the weight of the wheels, the train would be continually climbing up the hollows in the rails, which would require a comparatively extremely large amount of energy.

20 In the same way, to carry the illustration to the extreme, a horn made of flexible rubber would absorb a large amount of energy by the compression and expansion of the rubber. Many present day horns are subject to this same difficulty, although of course in lesser degrees than would be a rubber horn.

25 I have found that the ratio between the area at the orifice (5) and the area at the mouth of the horn (3) should be as great as possible, as this ratio represents in a measure the "load" effect upon the diaphragm of the sound producing instrument. I have also found that the connection between the sound producing instrument (6) and the orifice (5) must be tight and uniform.

30 The device which forms the subject of my invention may preferably be formed in one piece of porcelain, earthenware or other ceramic material, and will thus be strong, rigid, durable, and attractive in appearance. It is preferable that the ceramic material be glazed, particularly inside of the horn and orifice, although many surprising results can be secured without glaze. In the device which I have invented, the horn provides walls or sides which enclose the telephone receiver or other sound producing device and at the same time offer means of supporting the horn in place on a table or against the wall.

35 The horn which I have invented is also relatively stable, not subject to overtones,

and is of such form and contour that it may be conveniently placed on any table or support without occupying a great deal of space.

By curving the constricted portion of the 70 device (4), as shown, the effective length of the horn is materially increased without requiring any greater space and without involving an ugly appearance.

75 The construction also protects the delicate telephone receiver from shocks, jars, dust, dirt, handling, etc.

If desired, the space beneath the horn is sufficient to permit the placing of batteries, tubes, or other auxiliary equipment.

80 One practical method of producing the horn which I have invented is to cast it in a single piece by the so-called casting process, in which a porcelain slip, composed primarily of clay diluted with water, is 85 poured into a plaster of Paris mold and allowed to harden by the absorption of water by the plaster of Paris. I do not wish to be restricted to this manufacturing method alone, as many other methods may be employed, but the casting process is cheap, simple, and highly satisfactory, particularly as it gives a dense, hard, smooth, uniform surface on the interior (and exterior) of the horn.

85 The device which I have invented may be modified in numerous obvious ways and numerous other materials may be substituted without departing from the spirit of this invention. For instance, while the exact 100 form and contour which I have shown and described is considered by me to be the most desirable form for the commercial use of this invention, yet this invention is broader than the mere shape or contour, and covers 105 materials as well. Thus a horn similar in contour to those now commercially employed for radio purposes but constructed of ceramic material, as described above, I consider to be within the scope of my invention.

110 Obvious modifications in form and contour will be apparent to those skilled in the art, and these modifications still come within the scope of my invention.

115 It should be understood that the construction of my horn in a single unit is of considerable advantage in attaining the objects of this invention. In other words, the smooth continuous surface inside the horn, free from breaks, crevices or all forms of discontinuities contributes to the success of my invention. Further, the fact that the material is the same for the entire travel of the sound waves in the horn, is of importance, as I have found that horns made up 120 of several sections, some of which are metal and some wood or papier mâché, are less satisfactory than a unit construction such as I have invented. It also insures permanence, as there are no individual sections 125 130

to loosen or lose their shape or alignment. It also appears that the sound wave suffers a loss or distortion on passing from a section having one set of characteristics to a section of different characteristics, as from metal to wood or papier mâché, and vice versa.

As a theory, which seems plausible from my study of horns, it is possible that in addition to the rigidity, stiffness and lightness of ceramic materials, the relatively low heat conductivity is one factor which serves to make these materials so well suited for sound amplifying purposes. I do not wish to restrict my invention to this theory, but am advancing it only as a means of explaining the superior results secured by me with horns constructed with ceramic materials.

It will be noted from the drawing that the upper and lower lips of the horn device project forward beyond the side walls of the horn. The practical effect of this construction is to give a sound distribution outside the horn which will have a greater volume at points in the same horizontal plane of the horn than at points materially above or below the principal axis of the horn.

One well known defect of present reproducing devices arises from the fact that if the listener is a relatively short distance at one side of the axis of the sound horn, sounds are much reduced in volume and somewhat distorted. Inasmuch as it is uncommon for the horn to be placed materially below or above the listener's ear, the device which I have invented will distribute the sound throughout the space where it is most desired.

In other words, speaking non-technically,

the design of my horn is such that the sound is directed through a wide angle in a horizontal plane but through a relatively narrow angle in a vertical plane.

Another means which I have found contributes to the successful operation of the horn, is the upwardly turned point or peak in the top lip. This peak serves to noticeably reinforce the volume of the sound in front of the horn, and from a manufacturing standpoint materially helps in the stiffening of the upper wall, which without this peak or arch construction would have a tendency to sag in the process of manufacture or during the firing of the ceramic material.

It will also be noted, that while the axis of the larger portion of the horn is substantially horizontal or inclined slightly downward, the axis of the smaller end of the horn is substantially vertical. It will also be noted that the larger portion of the horn, which is the portion having the horizontal axis, is much greater in length than the smaller portion of the horn, or the portion which has the vertical axis. I have found that the greater the length of the axis of the large portion of the horn, the greater the loading effect of the telephone diaphragm, the less the distortion and the greater the volume of sound produced.

Having now fully described my invention, what I claim as new and wish to secure by Letters Patent in the United States, is as follows:

1. A sound amplifier of glazed porcelain.
2. A sound amplifier of porcelain.

WILLIAM A. DARRAH.
